(57) **CLAIM**

I claim the ornamental design for a utility direct charge LED flashlight, as shown and described.

DESCRIPTION

FIG. 1 is a top rear perspective view of a utility direct charge LED flashlight according to the new design;

FIG. 2 is a bottom front perspective view of the utility direct charge LED flashlight illustrated in FIG. 1;

FIG. 3 is a top front perspective view of the utility direct charge LED flashlight illustrated in FIG. 1;

FIG. 4 is a bottom rear perspective view of the utility direct charge LED flashlight illustrated in FIG. 1;

FIG. 5 is a rear side elevational view of the utility direct charge LED flashlight illustrated in FIG. 1;

FIG. 6 is a left side elevational view of the search direct charge LED flashlight illustrated in FIG. 1;

FIG. 7 is a front side elevational view of the utility direct charge LED flashlight illustrated in FIG. 1; and,

FIG. 8 is a right side elevational view of the search direct charge LED flashlight illustrated in FIG. 1.
